[57] ABSTRACT

[22] Filed: July 8, 1971

The invention concerns the coloration of hot melt polymers by direct injection of a dye into the polymer stream during polymerization, e.g., before feed to a spinning machine.

[21] Appl. No.: 160,812

A feed pump raises the dye pressure to approximate to that of the polymer at the injection point and a gear or turbine pump provides and controls continuous flow injection of the dye from the feed pump into the polymer stream.

FIG. 1.

FIG. 2.

COLORATION OF HOT MELT POLYMERS

This invention relates to the coloration of hot melt polymers and has for its object to provide improved apparatus for the direct injection of a dye into a polymer stream during polymerization. It is of particular advantage in the coloration of hot melt polymer immediately prior to the latter being fed to a spinning machine.

According to the invention, apparatus for the coloration of a hot melt polymer by direct injection of the dye, in solution or suspension, into a continuous polymer stream temperature-controlled for progressive polymerization, as in a continuous polymerization coil, comprises a feed pump for raising the dye pressure to approximate to that of the polymer at the injection point, and a gear or turbine pump for continuous-flow injection of the dye from the feed pump into the polymer stream and for measurement and control of the rate of injection.

The apparatus preferably includes a dye-mixing tank with continuously operating agitating or stirring means therein and providing the input to the feed pump. The dye pressure may then be determined and controlled by means of a relief valve in a feed-back path from the output side of the feed pump.

In a preferred arrangement according to the invention, a three-gear pump in a temperature-controlled zone is used for dye injection, and polymer is bled upstream of the injection point for preliminary mixing with the dye in the three-gear pump.

The invention provides for dye injection into a continuous polymerization coil or the like in a continuous flow free of pulsations such as are associated with piston or diaphragm pumps, and therefore making for uniform coloration. The gear-type pump providing the continuous-flow injection, being operated in a pressure-balanced condition, also ensures accurate metering, making for good control of color and of the facility of repeating a color.

Two forms of apparatus for the coloration of hot melt polymers, representing embodiments of the invention, will now be described by way of example, and with reference to the accompanying drawings, in which:

FIG. 1 illustrates the first of the forms of apparatus, and

FIG. 2 illustrates the second form of apparatus.

In each case polymer salt flows through a continuous polymerization coil 1 in a temperature-controlled zone and is delivered into a manifold 2 supplying the individual metering pumps which feed the spinnerets of a spinning machine. Colorization is achieved, with or without a measure of premixing, by direct injection of a dye solution or suspension into the polymer stream in the polymerization coil. Dispersement or final dispersement of the dye in the polymer salt results from the violent boiling action of the salt in the coil.

In one embodiment the dye in a water or glycol solution or suspension is stored in a mixing tank 3 fitted with a rotary-paddle type agitator 4 and with an outlet 5 connected to a feed and recirculating pump 6, the excess pump capacity being recirculated back to the dye mixing tank through a line 7 and a relief valve 8 which controls the delivery pressure. This recirculation assists in agitation of the dye solution or dispersion. The dye passes from the feed-pump 6, at a pressure determined and controlled by the relief valve 8, to a two-gear injection pump 9, the outlet 10 of which leads directly to a

tapping point 11 in the continuous polymerization coil 1 for dispersement of the dye as already described.

In operation, the feed-pump pressure is adjusted to match the polymer pressure at the tapping point 11 so that the two-gear injection pump 9 operates in a pressure balanced condition. This ensures accurate metering and permits effective control of the rate of injection.

In an alternative arrangement, a three-gear injection pump 12 in a temperature-controlled zone 13 is employed in place of the two-gear pump 9 and partially polymerized salt from the continuous polymerization coil 1 is bled from a point 14 upstream of the injection point 11 into the three-gear pump 12 for pre-mixing.

The pump 12 has a pair of inlet ports 15 and 16 and a single outlet port. The three gears of the pump are arranged (as shown) for rotation about aligned parallel axes. Rotation of the gears effects mixing of the liquid flows entering through the inlet ports 15 and 16 and delivery thereof under pressure through the outlet port.

In this arrangement, a dye feed-pump of controlled delivery pressure is employed as before. It is coupled to one inlet port 15 of the three-gear injection pump 12. The polymer salt bled from the coil 1 is fed to the other inlet port 16 so that a measure of premixing of the dye and the polymer salt takes place in the three-gear pump 12, which is maintained at a temperature above the melt temperature of the polymer being used. The three-gear pump 12 injects the mixture into the continuous polymerization coil 1 at injection point 11 so that final mixing is achieved by the boiling action within the coil.

In order to ensure accurate metering, the three-gear injection pump 12 is operated in a balanced pressure condition by adjusting the dye feed pressure to match the polymer pressure at the point of injection, and arranging the bleed tapping close to the injection point (but sufficiently removed to minimize recirculation of the injected dye), so that the pressure difference between the point of bleed and the point of injection is small.

Premixing of the dye and polymer assists in complete final dispersion of the dye. It has a further advantage in that wear of the pump gears is reduced when an abrasive dye additive is used as compared with handling only the dye in the injection pump.

We claim:

1. Means for feeding colored hot melt polymer to the spinnerets of a spinning machine, said feeding means comprising a polymerization coil through which the hot melt polymer is delivered to the spinnerets, said coil having an injection point; a rotary pump; a line connecting the rotary pump to the injection point; a dye mixing tank; and a feed pump for delivering concentrated dye under a predetermined controllable pressure directly from the tank to the rotary pump for continuous flow injection of the concentrated dye into the hot melt polymer passing through the coil.

2. Means for feeding colored hot melt polymer to the spinnerets of a spinning machine, said feeding means comprising a polymerization coil through which the hot melt polymer is delivered to the spinnerets, said coil having an injection point and a bleed point disposed upstream of the injection point; a rotary pump having a mixing facility, said rotary pump having a pair of inlets and an outlet; a supply line connecting the bleed point and one of the inlets of the rotary pump; a delivery line connecting the outlet of the rotary pump and

the injection point; a dye-mixing tank; and a feed pump for delivering concentrated dye under a predetermined controllable pressure from the tank to the other inlet of the rotary pump for admixture with hot melt polymer

fed to the rotary pump along the supply line to obtain continuous flow injection of colored polymer along the delivery line into the polymerization coil.
